CLAIM

The ornamental design for sliding cover for reel seat of fishing rod, as shown and described.

DESCRIPTION

FIG. 1 is a perspective view of sliding cover for reel seat of fishing rod embodying my new design;

FIG. 2 is a top plan view thereof;

FIG. 3 is a front elevational view thereof;

FIG. 4 is a left side elevational view thereof; and,

FIG. 5 is a right side elevational view thereof.

The bottom view is a mirror image of the top view, and the rear view is a mirror image of the front view;
